CLAIM

The ornamental design for a smart interactive display board, as shown and described.

DESCRIPTION

FIG. 1 is a front view of a smart interactive display board; FIG. 2 is a rear view thereof; FIG. 3 is a left side vertical view thereof; FIG. 4 is a right side vertical view thereof; FIG. 5 is a top view thereof; FIG. 6 is a bottom view thereof; FIG. 7 is a top rear perspective view thereof; FIG. 8 is a bottom rear perspective view thereof; FIG. 9 is an enlarged detail view of FIG. 1; FIG. 10 is an enlarged detail view of FIG. 1; FIG. 11 is an enlarged detail view of FIG. 4; FIG. 12 is an enlarged detail view of FIG. 8; and, FIG. 13 is an enlarged detail view of FIG. 8.

The even-dash broken lines show portions of the article which form no part of the claimed design. The dash-dot broken lines, encircling portions of the smart interactive display board, represent the extents of the detail views and form no part thereof.
